UNITED STATES PATENT OFFICE.

HORACE S. BOYNTON, OF OSHKOSH, WISCONSIN.

TENONING-MACHINE.

SPECIFICATION forming part of Letters Patent No. 329,007, dated October 27, 1835.

Application filed December 19, 1834. Serial No. 150,724. (No model.)

To all whom it may concern:

Be it known that I, HORACE S. BOYNTON, a citizen of the United States, residing at Oshkosh, in the county of Winnebago and State 5 of Wisconsin, have invented certain new and useful Improvements in Tenoning-Machines; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 My invention, to be hereinafter claimed, relates to improvements in sash and door tenoning machines, and particularly to the mechanism for supporting, adjusting, and operating the cutter-heads, for supporting, holding, 20 and carrying the material, and for cutting the tenons and clearing away the chips.

My invention, hereinafter described, may be readily understood by reference to the accompanying drawings, in which—

25 Figure 1 is a side elevation of a tenoning-machine embodying my improvements. Fig. 2 is an end view (left end) of same machine. Fig. 3 is a cross-section on line xx of Fig. 1, and having a part of the case inclosing the 30 presser-feet broken away. Figs. 4, 5, 6, 7, 8, 9, 10, 11, 12, and 13 are details.

The same parts are indicated by like reference numbers or letters in all the views.

1 is the supporting-frame. 2 is the driving 35 shaft, extending lengthwise of the frame, with bearings in the lower part of said frame and having proper connections with the extrinsic power by which it is driven. Upon one end of the frame 1, and rigid thereto, is the small 40 raised platform 3, and at the other end, and traveling thereon, is the movable platform or carriage 4, which platform and carriage each support frames carrying mechanism hereinafter described. This carriage 4 is made to 45 travel on the frame 1 toward and from the rigid platform 3 by means of the mechanism shown in Figs. 1, 3, and 4. Beneath the carriage 4, lengthwise of and rigid at its end to the frame 1, is the screw-threaded rod 5, and 50 traveling thereon the internally-screw-threaded mitered pinion 6, which pinion is provided on its rear with a flange having a groove in

its periphery, in which groove the lower forked end of the hanger 7, rigid to the carriage 4, fits movably. The crank-rod 8, having its 55 bearings in the carriage 4, is provided at its inner end with a mitered pinion meshing with the pinion 6, and at its outer end with the crank-handle 9, by the turning of which the travel of the carriage 4 is effected through the 60 mechanism just described.

On the platform 3 and carriage 4, respectively, is a circular plate or disk, 10, Fig. 10, having on its under side, around near its periphery, a flange or lip extending downwardly 65 and outwardly, forming with the under side of the disk a groove adapted to receive and move upon the ring 11, which ring is rigidly affixed to the upper surface of the platform 3 and carriage 4, respectively, and upon which 70 ring 11 said disk 10 is supported and rotates horizontally. The disk 10 is provided on its periphery with the lug or catch 12, adapted to impinge against the pin 13, which is rigid in and extends upwardly from the top of the 75 platform or carriage, whereby the rotation of the disk 10 is checked, and against which it is held. The disk 10 is also provided with the rigid upturned lugs or flanges 14, to which the upright frame 15, carrying the cutter-heads and other mechanism, is affixed.

Supported by and having a vertical movement in grooved ways upon the face of the frame 15 is the upturned yoke 16, provided with journal-bearings adapted to receive and 85 support the horizontal arbor 17, which carries the lower cutter-head, 18. This arbor 17 has rigid thereto a belt-driven pulley, 19, and carries the cutter-head on its front or projecting outer end. Above the yoke 16, and supported 90 by and having a vertical movement in grooved ways on the frame 15, is the bracket 20, provided with journal-bearings adapted to receive and support the horizontal arbor 21, which carries the upper cutter-head, 22. This arbor 21 95 has rigid thereto a belt-driven pulley and carries the cutter-head 22 on its projecting front end. The bracket 20 is supported by and is raised or lowered with reference to the yoke 16 by means of the screw-threaded rod 23, 100 which passes vertically through and has a screw adjustment in the bracket 20, and rests at its lower end upon the top of the yoke 16. This rod at its upper extremity has a hand-

wheel, 24, rigid thereto, by turning which said bracket is raised or lowered with reference to the yoke 16, as described, and said bracket may be clamped to the frame 15 by turning 5 the hand-wheel *a*.

The yoke 16 and bracket 20 are both raised and lowered concurrently by means of the screw-threaded rod 25, which passes vertically from below up into and has a screw adjustment in the yoke 16, and is supported by a rigid collar thereon, resting upon the disk 10, through which the rod passes, and below which it is provided with the rigid mitered pinion 26, which meshes with a mitered pinion 15 or the horizontal rod 27, which rod 27 has its bearings in platform 3 or carriage 4, respectively, and is provided at its outer extremity with the rigid hand-wheel 28, by the turning of which said yoke 16 and bracket 20 are raised 20 or lowered concurrently, as described, and the yoke 16 may be clamped to the frame 15 by turning the hand-wheel *b*. Above the bracket 20 is the belt carrying and tightening idle-pulley 29. This pulley has the bearings of its 25 journals in the outer ends of two arms, 30, pivoted at their inner ends in a nearly horizontal position to the top of the frame 15. These arms 30 are each provided with a segmental arm, 31, rigid thereto in front of the 30 pivotal point of said arms and extending downwardly and to rearward of the pivotal point of said arms, and at their respective rear ends have attached thereto a cord or strap, which strap at its other extremity is attached to and 35 winds over to the front on a shaft having its bearings in the brackets 20, and which on its outer end has rigid thereto the pulleys 32, over and upon which runs a cord attached thereto at one end, and supporting at its other end the 40 weight 33, which weight, by its gravity, rotates the pulley 32 and winds up the strap, thereby pulling down on the rear end of the segmental arm and throwing up the front end of the arms 30, tightening the belt running over 45 the pulley 29, carried thereon. The belt-pulleys on arbors 17 and 21 and the pulley 29 are, when the disk 10 is swung around placing the cutter-head in position for work, located vertically above a driving-pulley, 34, on the driving-shaft 2, and over and upon all these runs the driving-belt 35. A revolving coping-tool, 36, is fixed on the lower end of a vertical arbor having its bearings in boxes rigid to the bracket 20, and is driven by a belt over the 50 pulley 37 on the arbor that carries the tool. A similar reversed coping-tool, 38, upon a vertical arbor, having its bearings in boxes upon the yoke 16, is driven by a belt over the pulley 39 on said arbor. These coping-tools 55 cut the coping-recess within the shoulder on the stuff at the inner end of the tenon, doing their work just after the cutter-heads have formed the tenons.

40 are segmental arms, respectively pivoted 60 at their inner ends upon an arm or rod affixed to bracket 20, and extending outwardly therefrom parallel with the arbor carrying the cut-

ter-head, which arms at their outer extremities carry a chip-breaker, 41, Figs. 1 and 3, extending from one arm to the other and rigid 70 thereto, and so constructed as when thrown down upon the stuff in the rear of the cutter-head to catch and remove the chips, and when not in use to be thrown back away from the cutter-head.

Upon the yoke 16, in the rear of the lower cutter-head, and directly beneath the upper cutter-head, is the vertically-adjustable bracket 42, having a horizontal top face adapted to receive the under surface of the tenon just cut 80 by the lower cutter and support it firmly against the work of the upper cutter. This bracket has a vertical slot, through which passes the set-screw bolt 43, which bolt fits into and works in a corresponding screw-thread in the yoke 16, whereby said bracket is supported and can be adjusted up or down, 85 as desired.

A similar corresponding reversed bracket, 44, is adjustably attached to the bracket 20, 90 and is adapted to bear upon the upper surface of the tenon and steady it while the upper cutter and the coping-tools are doing their work. The stuff is supported and fed to the cutters upon a carriage consisting of the two 95 endless sectional racks 45, running over the idle-wheels 46, and supported on a frame and driven by mechanism hereinafter to be described. The endless racks are constructed in links or sections pivoted together, as shown 100 in Fig. 7, each section having on its under side lateral cogs so formed that when the sections are pivoted together they form a continuous rack, which runs upon and is driven by the pinion 47 on driving-shaft 48. Rigid 105 on the outer surface of the endless racks 45, at equal and convenient distances are the lugs 49, adapted to catch the stuff placed on the carriage and force it forward on the carriage. These endless racks are each supported 110 upon a frame, 50, extending longitudinally across the machine and in the line of movement of the stuff to be operated upon. These frames 50 are supported by legs 51 and 52, which on side 51 are rigid to the platform 3 115 and carriage 4, respectively, and on the other side, 52, rest upon the frame 1. These frames 50 have each two parallel walls connected together by a cross bottom wall, as shown in cross-section in Fig. 8. The idle-wheels 46 120 have bearings and are supported in the respective ends of the frames 50. These frames 50 have each a sliding extension end, 53, having one or more slots, through which pass the screw-threaded bolts 54, which bolts fit and 125 turn in corresponding screw-threads in the main part of the frame 50, and by which slots and bolts said extension end of said frame may be adjusted out or in, and are adapted to tightening the endless racks 45. The top of 130 these frames 50 are each provided with a longitudinal groove, (shown in section in Fig. 8,) in which said endless rack 45 runs and is supported. The pinions 47 each have rim 55,

having peripheral cogs, which rim is adjustably affixed to an encompassed sleeve, 56, by set-screws 57, through a slot in the flange of said sleeve into a flange on said rim, as shown in Figs. 5 and 8, whereby any wear on the cogs may be taken up and the rim brought firmly up to its work against the cogs of the rack in one or all of these pinions, whereby the endless racks are made to run evenly and truly with relation to each other, and thereby carry the stuff squarely up to the cutters. This adjustment is accomplished by means of the set-screw bolt 58, provided with a cam, 59. (Shown in Figs. 5 and 9.) This bolt 58 passes through an aperture in the flange of sleeve 56 and screws into the flange of the rim 55.

On that part of the bolt within the aperture in the sleeve is the cam 59, so that by turning this bolt slightly the sleeve is rotated slightly forward or backward with reference to the rim 55, and is held in position by the set-screw bolts 57. The sleeves 56 encompass and fit upon the shaft 48, and are adjusted thereto at the carriage (4) end of the shaft by an inwardly-extending feather, 60, which projects therefrom into a groove extending longitudinally on said shaft, whereby said sleeve is caused to rotate with said shaft, but has a free longitudinal sliding movement thereon, and at the other end of the shaft the sleeve is made rigid to said shaft by a key inserted in said groove in the shaft and in a corresponding groove in the sleeve. The pinions 47 are each supported on the frames 50 by a circular flange or ring, 61, which ring is provided with a wing, by and through which said ring is affixed rigidly to the frame 50, and said ring fits into a groove in the face of the pinion, as shown in Figs. 6, 8, and 9, and on this circular flange or ring said pinion rotates.

The shaft 48 is driven by the cog-wheel 62, rigid upon the end thereof, which meshes with a pinion on the shaft 63, which shaft 63 is in turn driven by the belt-wheel 64, rigid thereon, and over and upon which wheel runs a belt, which also runs upon and is carried by a small wheel on shaft 65, which shaft is driven by the friction-wheel 66, rigid thereon, bearing against a small friction-wheel, 67, on the driving-shaft 2.

The shaft 65 has its bearings in a sleeve, 68, Fig. 1, which sleeve is supported at its inner end in a ring pivoted to the frame 1, and at its outer end in a lever, 69, Fig. 2, which lever is pivoted at its inner end onto the frame 1, and at its outer end is preferably provided with the weight 70, which by its gravity carries the shaft 65 down, so that the wheel 66 is pressed against the wheel 67, as hereinbefore stated. To the outer end of lever 69 a link, 71, is attached, the upper end of which is attached to the outer end of the crank-arm of shaft 72, which shaft has its bearings in brackets rigid to the frame 1, and is provided with a rigid hand-lever, 73, whereby it can be rotated a part of a revolution, thereby raising lever 69 and throwing friction-wheel 66 out of

contact with wheel 67, releasing the feeding mechanism from the driving-shaft and stopping the feed.

Vertical shafts 74, having their bearings in brackets made fast in and supported by the platform 3 and carriage 4, respectively, are driven by the belt 75, passing over a fast pulley on the bottom of said shaft and over a pulley fast on the driving-shaft 2, which belt is tightened by the adjustable idle-wheel 76, having its bearings adjustable up or down by the set-screw 77. Upon the shafts 74 are the fast pulleys 78 and 79, upon which belts are carried, that also run upon the pulleys 37 and 39, respectively, and drive the shafts carrying the upper and lower coping-tools, 36 and 38.

The upright brackets or standards 80 at their lower extremities are rigid to and supported upon the platform 3 and carriage 4, respectively. Rigid to the two of these standards 80, that are at the front side of the machine, are horizontal brackets supporting guards 81 and 82. The guard 81, on the left-hand side, is adjustable on its bracket toward and from the carriage by means of the slots in the bracket and legs on the guard passing through said slots and secured by the set-screws 83 thereon. The guard on the right side of the machine is shown in detail in Figs. 11 and 12. This guard, for convenience, preferably extended somewhat higher than the guard on the left side has an inward inclination downwardly, so that stuff as it is delivered to the machine may be readily placed between the guard on the left and this one, and as it comes to rest at the bottom of the guard and upon the carriage, the stuff will be caused to take its proper position firmly against the guard at the left of the machine, from which place it is to be carried forward in the same position by the endless racks to the cutter-heads. This guard 82 is mounted upon a bottom, 84, having a sliding movement toward and from the carriage, being provided with one or more securing lugs or bolts, 85, rigid thereto, passing downwardly through slots in its supporting-bracket, and also with a lug, 86, rigid thereto, also extending downwardly through a slot in said supporting-bracket, in which lug 86 a horizontal rod, 87, is affixed at one end, the other end of said rod being supported by and having a horizontal movement in a lug affixed to said bracket, and around which rod is a spiral spring, 88, adapted to hold said guard against the stuff, but sufficiently yielding to accommodate between the guards from time to time pieces of slightly varying length. These guards have their bottom on a level with the top of the carriage. These standards 80, in pairs on the platform 3 and carriage 4, respectively, support on their upper extremities presser-feet 89 in sets, one set supported by each pair of standards. The case 90, inclosing these presser-feet, consists of a longitudinal box or frame attached to the upper ends of the standards 80, above and parallel with the carriage. The presser-feet,

in sets or series, having their soles slightly below the case 90, are provided with upwardly extending shanks having their bearings in and supported by said case and having a vertical movement therein.

Within said case, around said shanks, are spiral springs 91, resting at their upper ends against said case and at their lower ends against a pin or lug in said shanks, whereby 10 said feet are given a downward pressure limited by the supporting pins through the tops of the shanks above the upper bearings. The case 90 is attached to the standards 80 by a screw-threaded bolt, which passes through a 15 vertical slot, 92, in the standards into said case, and said case is adjustable vertically by means of the screw-threaded rod 93, supported, near its upper end, by a shoulder resting upon a shoulder of the standards and passing downwardly through said shoulder on said standards into said case 90, in which case said rod turns upon a screw-thread thereon and a corresponding screw-thread within said case, whereby said case may be raised or lowered, 20 and may be fixed in position by the set-screw passing through the slot 92.

The rods 93 are provided with rigid mitered pinions at their upper extremities, which mesh with pinions 94 on the horizontal rod 95, 30 which rod has its bearings in the top of the standards 80, and can be rotated by the hand-wheel 96, rigid thereto, thereby raising or lowering the case inclosing the presser-feet.

The cutter-heads 18 and 22 carry the knives 35 that cut the tenon on the stuff. These cutter-heads are provided with scroll-like surfaces, on which the knives are affixed, and this peculiar form of surface I do not claim in this application, but reserve the same for a 40 separate patent to be hereafter applied for by me according to law.

The shaft 48, beside the supporting-sleeve 54 and flange 61, hereinbefore described, is also supported and has bearings at its respective ends in the standards 97, rigid upon frame 1.

It will be seen that the carriage 4, and the machinery thereon supported, may be readily moved toward or from that end of the machine on which the platform 3 is by rotating the crank 9 through the devices 5 and 6, 7 and 8 therewith. When this carriage is so moved, it also carries with it the belt-pulleys 98 and 99 on the driving-shaft 2 by the hanger 55 100, rigid to said carriage, beneath and at its lower forked extremity, riding within and bearing against the sides of a groove within a sleeve, which sleeve is rigid to and connects said pulleys 98 and 99 and surrounds the shaft

60 2. 101 is a tight pulley on shaft 2, by which power is applied thereto through a belt to drive the mechanism, and 102 is a loose pulley on said shaft, upon which said belt may be thrown to release the shaft 2 from the driving-power.

In Fig. 1 the dotted lines indicate a piece of stuff (door-rail) on the carriage being car-

ried forward against the cutting-tools, which on the left are shown in position doing their work. On the right the disk 10 is thrown 7c around, placing the cutter-heads and other devices thereon outside, away from their work and in a position in which they can be readily repaired or the knives sharpened.

I do not deem it necessary to further describe the operation of this machine, as its operation from the foregoing description of parts will be readily understood by all persons familiar with this class of machines; but by the duplicate sets of tools, one at each end 80 of the frame 1, I am enabled with this machine to cut and cope the tenon on both sides and at both ends of the stuff at one and the same time, and I can readily adjust these duplicate 85 sets of tools at such distance from each other as to cut stuff of greatly varying length.

What I claim as new, and desire to secure by Letters Patent, is—

1. In a tenoning-machine, the combination of the rotating disk 10, mounted upon a supporting-frame, with the thereon supported cutter-heads 18 and 22, and the mechanism connected therewith, substantially as and for the purpose described.

2. In a tenoning-machine, the combination 95 of the lower cutter-head, 18, with the upper cutter-head, 22, located in the rear of said lower cutter-head and so as to cut the stuff on the opposite side from the side cut by the knives in the lower head, and the adjustable bracket 100 42, located opposite to the rear cutter-head, 22, and adapted to hold the stuff up to the rear cutter, 22, substantially as and for the purpose described.

3. In a tenoning-machine, the combination 105 of the lower cutter-head, 18, with the upper cutter-head, 22, located in the rear of the lower cutter-head, 18, and so as to cut the stuff on the opposite side from the side cut by the knives in the lower head, the adjustable 110 bracket 42, located opposite to the rear cutter-head, 22, and adapted to hold the stuff up to the rear cutter, 22, and the adjustable bracket 44, located close in the rear of the rear cutter-head, 22, and adapted to steady the stuff 115 by bearing against it on the side dressed by the front cutter, 18, while the rear cutter is still cutting the stuff, substantially as and for the purpose described.

4. In a tenoning-machine, the endless rack-driving pinion 47, supported and rotating on the annular brackets 61, rigidly affixed to the frame 50, said pinions consisting of the cog-provided periphery 55, adjustably affixed to the encompassed sleeve 56 by set-screws 125 57 through slots for said adjustment, which adjustment is accomplished by the bolts 58 and cam 59, said sleeve rotating with but being movable longitudinally on the shaft 48, in combination with the endless racks 45, substantially as and for the purpose set forth.

5. In a tenoning-machine, the combination of the adjustable guide 81, located on the frame at one end of the machine and in front

of the cutter-heads, with the adjustable and movable guide 82, located opposite thereto on the frame at the other end of the machine, and adapted to receive the stuff between them and adjust it in position to be carried forward therefrom by the endless racks, substantially as described.

6. In a tenoning-machine, the upper and lower cutter heads, 18 and 22, one of said heads being located in the rear and on the opposite side of the stuff from the other head, said heads being each supported on an arbor provided with a driving-pulley, the adjustable bracket 42, located and adapted to support the stuff while being cut by the rear cutter, and the belt-tightening pulley 29, located and adapted for tightening the driving-belt running upon said tightening-pulley, and the two cutter-head driving-pulleys, all supported upon and in combination with the horizontal rotating disk 10, substantially as and for the purpose set forth.

7. In a tenoning-machine, the endless racks 45, in combination with the idle-wheels 46, located and supporting the racks 45 at the two ends of their circuits, respectively, the frame 50, provided with the adjustable extension end 53, in which one pair of said idle-wheels 46 is supported, and by which the tension of the racks 45 may be adjusted, and the independent driving-pinions 47, located midway between the ends of said circuits of said racks, said pinions being adapted to drive said racks forward by power applied to said racks through said pinions, substantially as described.

8. The screw-threaded rod 5, rigid at its end

to frame 1, the thereon-traveling internally-screw-threaded mitered pinion 6, and the crank-rod 8, supported in carriage 4, and having at one end a mitered pinion meshing with pinion 6 and at the other end a crank-handle, 9, in combination with the carriage 4, traveling on frame 1, and provided with the rigid hanger 7, the lower forked end of which rides movably in a groove in the pinion 6, and frame 1, substantially as described.

9. The friction-wheel 66, rigid on shaft 65, shaft 65, supported and rotating in sleeve 68, and sleeve 68, having a pivotal support at its inner end, in combination with lever 69, pivoted at one end on the frame 1 and supporting the outer end of the sleeve 68, said lever 69 being adapted to be raised and lowered, causing the friction-wheel 66 to engage against or be released from the wheel 67 on driving-shaft 2, substantially as described.

10. The sleeve 68, in which the shaft 65, carrying friction-wheel 66, is supported and rotates, having its inner end pivotally supported on frame 1 and at its outer end supported in lever 69, and lever 69, pivoted at one end on frame 1, in combination with the link 71, connecting the outer end of lever 69 to the crank-arm of shaft 72, and shaft 72, having its bearings in frame 1, and provided with a lever-handle, 73, substantially as and for the purpose described.

In testimony whereof I affix my signature in presence of two witnesses.

HORACE S. BOYNTON.
